(57) **CLAIM**

The ornamental design for a dumbbell support, as shown and described.

DESCRIPTION

FIG. 1 is a perspective view of a dumbbell support showing our new design according to a first embodiment.

FIG. 2 is a front elevation view thereof.

FIG. 3 is a left-side elevation view thereof, the right-side elevation view being a mirror image of the left-side elevation view.

FIG. 4 is a top plan view thereof.

FIG. 5 is a bottom plan view thereof.

FIG. 6 is a rear elevation view thereof.

FIG. 7 is a perspective view of a dumbbell support showing our new design according to a second embodiment.

FIG. 8 is a front elevation view thereof.

FIG. 9 is a left-side elevation view thereof, the right-side elevation view being a mirror image of the left-side elevation view.

FIG. 10 is a top plan view thereof.

FIG. 11 is a bottom plan view thereof; and,

FIG. 12 is a rear elevation view thereof.

The broken lines form no part of the claimed design.

1 Claim, 6 Drawing Sheets
